UNITED STATES PATENT OFFICE.

WILLIAM MADDEN, OF SAN FRANCISCO, CALIFORNIA.

SHIELD FOR BOILER-FURNACES.

SPECIFICATION forming part of Letters Patent No. 356,285, dated January 18, 1887.

Application filed May 24, 1886. Serial No. 203,157. (No model.)

To all whom it may concern:

Be it known that I, WILLIAM MADDEN, of the city and county of San Francisco, and State of California, have invented a Shield 5 for Boiler-Furnaces; and I hereby declare the following to be a full, clear, and exact description thereof.

My invention relates to a shield or protection which is specially useful in connection 10 with boiler-furnaces where great heat is brought upon the angles and flanges of certain portions of the boiler.

It consists of a protecting shield for these 15 portions, by which they are relieved from the effects of excessive heat, and leakage by the constant unequal expansion and contraction is avoided.

Referring to the accompanying drawings for a more complete explanation of my invention, Figure 1 is a sectional elevation of a 20 boiler, showing the application of my device. Fig. 2 is a perspective view of the device.

In the present case I have shown my invention applied to boilers of that class having 25 large flues in the lower part, with grates upon which the fire is built, bridge-walls at the rear end, and a combustion-chamber at the rear of the bridge-wall into which the products of combustion pass, return-flues or small tubes 30 through which the heat and flame are brought, and the uptake and smoke-stack at the front of the boiler. These boilers are usually made short, and where the high pressure of steam is carried must be made correspondingly 35 thick and strong.

At the point *a* the flanges of the inner head or the flue sheet are turned and riveted to the shell of the furnace, making a lap joint and considerable thickness, and the exterior of 40 this angle is exposed to the most intense heat from the fire while the interior is in contact with the water of the boiler. The thickness of the metal is such that very unequal expansion takes place at this point, and the result 45 is a strain which causes leakage, so that it is

almost impossible to keep the joint tight, and the boilers need constant overhauling and repair on this account. In order to protect this portion from the direct action of the flame and heat of the fires, I form an arch of fire-clay or brick, as shown at *b*, which extends a short distance each side of the joint and prevents actual contact of the flame with it. 50 This arch may be either built of fire-brick or fire-clay. In the present case I have shown a semicircular iron arch or hoop having feet or flanges at the bottom, supported upon the bridge-wall at each end, and it is provided with 55 projecting lugs or ridges, *c*, within which the body of fire-clay or the fire-brick may be held and prevented from falling out of place. This 60 prevents the direct action of the heat upon the angle and prevents it from great and unequal expansion, which would otherwise take place, and prevents the strain and consequent leak- 65 age at this point.

Having thus described my invention, what I claim as new, and desire to secure by Letters Patent, is—

1. A protecting-shield for boilers, comprising 70 a flanged semicircular iron arch or hoop supported upon the bridge-wall, and provided with lugs or ridges for securing fire-clay or fire-brick, substantially as herein described.

2. In a boiler-furnace, a protecting shield or 75 arch formed of fire-clay, fire-brick, or other fire-resisting material, said arch or circle extending around the inner end of the tubular furnace and protecting the angle and flange at that point, in combination with an arch or 80 hoop having ridges or lugs, whereby the fire-brick or other substance is retained in position, substantially as herein described.

In witness whereof I have hereunto set my hand.

WILLIAM MADDEN.
